UNITED STATES PATENT OFFICE

123,001

DESIGN FOR A LACE STOCKING

Ernest Albin Nebel, Clifton, N. J.

Application January 16, 1940, Serial No. 89,496

Term of patent 3½ years

To all whom it may concern:

Be it known that I, Ernest Albin Nebel, a citizen of the United States, residing at Clifton, in the county of Passaic and State of New Jersey, have invented a new, original, and ornamental Design for a Lace Stocking, of which the following is a specification, reference being had to the accompanying drawing forming a part thereof.

Fig. 1 is a perspective view of a lace stocking embodying my new design; and

Fig. 2 is an enlarged detail view of a fragment of the stocking shown in Fig. 1.

I claim:

The ornamental design for a lace stocking, as shown.

ERNEST ALBIN NEEBEL.
